CLAIM

The ornamental design for a soccer ball, as shown and described.

DESCRIPTION

FIG. 1 is a front elevational view of a soccer ball showing my new design, the side opposite being a mirror image;

FIG. 2 is a top plan view thereof, the side opposite being a mirror image; and,

FIG. 3 is a right side elevational view thereof, the side opposite being a mirror image.

Fig. 1

Fig. 2

Fig. 3
